SYNCHRONIZING SYSTEM

Everhard H. B. Bartelink, Niskayuna, N. Y., assignor to General Electric Company, a corporation of New York

Application September 10, 1940, Serial No. 356,155

22 Claims. (Cl. 178—7.2)

My invention relates to a synchronizing system and has particular utility in its application to a television synchronizing system. More specifically, it contemplates a method and apparatus whereby the scanning action of a television receiving system may be maintained in accurate synchronism with the scanning action of a television transmitting system.

In present-day television systems utilizing cathode ray discharge devices for generating the picture signal at the transmitter and for reproducing the image at the receiver, means must be provided for synchronizing their operation. Ordinarily, in the transmitting picture signal generator a horizontal synchronizing signal is generated during each retrace interval following the end of each horizontal line traced by the cathode ray; and during the flyback interval following the end of each traversal of the picture area by the ray, a vertical synchronizing signal is generated. These signals are combined with the video signal, which is representative of the light and shade values of the image being scanned, and the complete signal is modulated upon a transmitted carrier. At the receiver a second cathode ray is caused to scan a fluorescent screen in a similar pattern. The intensity of this ray is controlled in accordance with the detected video signals in order to reproduce the image. The horizontal and vertical synchronizing signals are separated from the video signals and utilized to trigger the horizontal and vertical deflection generators, respectively. In this way the two cathode rays in the transmitter and receiver are maintained in synchronism, as is well understood by those skilled in the art.

Since the quality of the reproduced image is a function of the number of lines, the trend has been steadily in the direction of higher line frequencies to improve picture definition. This makes it more difficult to maintain synchronism. The use of interlaced scanning, wherein successive fields are staggered so that the lines of one field are interlaced with the lines of alternate fields, reduces flicker and thus reduces the necessary field frequency, as is well known. However, the problems of synchronization are not thereby simplified; rather, they are aggravated by the necessity of generating more complex synchronizing waves to maintain accurate interlace.

It is therefore broadly an object of my invention to provide an improved method and means for synchronizing the operation of a signal re-

ceiving system with the operation of a signal transmitting system.

It is further a main object of my invention to provide an improved method and means for synchronizing television transmitting and receiving systems.

It is a more specific object of my invention to provide an improved television synchronizing system in which transmitted horizontal and vertical synchronizing signals are composed of a plurality of component waves whose frequencies are definitely related in a particular way, whereby the respective signals may be separated from each other at the receiver through frequency discrimination in a simple and effective manner.

Another object of my invention is to provide line and field synchronizing waves having related, distinctive frequency characteristics, whereby they may readily be distinguished from each other at the receiving apparatus through the use of simple frequency selective circuits and whereby the possibility of any reaction between them, which might cause loss of synchronism or interlace, is minimized.

Another object of my invention is to provide an improved synchronizing system particularly suitable for use with interlaced television scanning apparatus having any desired degree of interlace, i. e., where any desired number of fields are interlaced to form one complete picture image or frame.

More specifically, in a preferred form of my invention the horizontal line synchronizing wave is analyzable into a fundamental component frequency wave and harmonics thereof and the vertical field synchronizing wave is resolvable into certain selected ones of said harmonics only. The difference in the frequency characteristics of the respective waves is utilized for differentiating between them at the receiver and for deriving horizontal and vertical synchronizing potentials therefrom.

Furthermore, in accordance with my invention all the synchronizing waves may be of equal amplitude since they are separated from each other by distinguishing between their frequency characteristics.

As an additional refinement, my invention contemplates a method and means for producing a composite synchronizing wave in which all the elements are not only of equal height but in which the average amplitude of the composite synchronizing wave remains substantially constant. Consequently, the power required for

generating and transmitting the synchronizing waves also remains substantially constant.

The features of my invention which I believe to be novel are set forth with particularity in the appended claims. My invention itself, however, together with further objects and advantages thereof, may best be understood by reference to the following description taken in connection with the accompanying drawings, in which Fig. 1 is a diagrammatic, conventionalized view of a complete television transmitting system embodying my invention; Fig. 2 is a diagrammatic, schematic view of a pulse generator embodying my invention and which may constitute an element of the transmitting system of Fig. 1; Fig. 3 is a group of curves illustrating the wave forms of waves developed at various points in the pulse generator circuit illustrated in Fig. 2; Fig. 4 is a diagrammatic, schematic view of an alternative form of pulse generator embodying my invention and which may constitute an element of the transmitting system of Fig. 1; Fig. 5 is a group of curves illustrating the wave forms of waves developed at various points in the pulse generator circuit illustrated in Fig. 4; Fig. 6 is a diagrammatic, conventionalized view of a complete television receiving system embodying my invention; and Figs. 7 and 8 are circuit diagrams of alternative forms of synchronizing signal separation circuits embodying my invention and which may constitute an element of the receiving system of Fig. 6.

In the television transmitting system illustrated in Fig. 1 a camera tube 30 of well-known form is provided for producing electrical current variations corresponding to the light and shade values of the image to be transmitted. The specific details of the camera tube 30 form no part of my invention and therefore need not be considered. Briefly, means are provided therein for developing and projecting an electron ray 31 against a sensitive mosaic target 32. The ray is caused to scan the target in a well-known manner through the action of suitable ray deflecting means. These deflecting means are represented as pairs of deflecting coils 33 and 34 which effect the scanning action along two coordinate axes in response to potentials applied thereto from the horizontal and vertical deflection generators 35 and 36, respectively. The camera tube 30 may also include the usual elements for controlling, focusing and accelerating the ray.

As the ray 31 scans the target 32, potentials are supplied to the video signal amplifier 37 corresponding to the conditions of illumination of the target at the instant of transversal by the ray. This action is also well known and need not be detailed.

The pulse generator 40, shortly to be described in greater detail, provides means for synchronizing the operation of the horizontal and vertical deflection generators 35 and 36 in a well-known manner. Horizontal and vertical synchronizing signals developed in the pulse generator 40 are indicated schematically as being supplied to the respective deflection generators 35 and 36 over the conductors 41 and 42. Various forms of apparatus for generating deflecting potentials and for effecting synchronization in response to the synchronizing signals are well known to the art. Therefore, it is thought unnecessary to detail specific circuits for accomplishing this result.

The output of video signal amplifier 37, comprising the amplified video signals, is supplied to the mixing amplifier, schematically indicated by

the block 43. In amplifier 43 the video signals are further amplified and are also combined, first, with the blanking pedestal, and, second, with the composite synchronizing signals (or supersynchronizing signals) which are indicated as being supplied thereto from the pulse generator 40 over the conductors 44 and 45, respectively. Again, the precise mechanism by which the signals are combined is immaterial to the practice of my invention and is omitted to simplify the description and to avoid undue complication of the drawing. Briefly, the blanking pedestal serves to maintain the signal level in the receiver at the level corresponding to "black" during the intervals between successive lines and fields traversed by the scanning ray 31. Thus the video signal is eliminated during these intervals. The composite synchronizing wave, to be described in greater detail shortly, is superimposed upon the blanking pedestal so that the synchronizing signals appear beyond the aforementioned level, namely, in the region which corresponds to "blacker than black."

The complete signal is supplied to the final stages of the television transmitting apparatus, indicated collectively by the transmitter 46. This comprises conventional apparatus by means of which the complete signal is modulated on a suitable carrier wave to be transmitted from the antenna 47. In the usual case, it may comprise the modulator, oscillator and power amplifier stages of the transmitter.

The various elements of the transmission system of Fig. 1 are supplied with power from a suitable power supply source. In order to simplify the drawing, this is indicated schematically by the common power supply source 48.

Fig. 2 illustrates more in detail one form of the pulse generator 40 which may be employed in the system of Fig. 1 for generating synchronizing signals in accordance with my invention. The composite elements of the pulse generator 40 comprise circuit elements well known to the art. Therefore, in the interest of simplicity and clarity of illustration, these elements have again been indicated only schematically in block form. It is believed that the details of specific circuits suitable for use in my system will readily be apparent to those skilled in the art in view of the following description.

The operation of the pulse generator of Fig. 2 will best be understood when considered in conjunction with the curves of Fig. 3 which represent the wave forms of electrical waves developed at various points in the pulse generator. They are to be considered as having a common horizontal time axis, so that points on the various curves on any particular vertical line, e. g., the dotted vertical line 49, corresponding to instantaneous values of the various waves at the same instant of time.

The master oscillator 50 in Fig. 2 generates a train of pulses which may, for example, be shaped to have the general form graphically illustrated by the wave 51 in Fig. 3. The term "pulse," as used in the specification and appended claims, is to be taken in its usual sense to describe a sudden amplitude variation in a signal including a departure from a reference value followed by a subsequent return to substantially the same value after a time interval. The wave 51 is seen to comprise a series of identical pulses 51a, of substantially rectangular wave form, which recur at uniform time intervals.

The output from the master oscillator 50 is supplied to a multi-vibrator 52. In a manner well

known to the art, this multi-vibrator 52 may be designed to generate a wave of a form which is similar to that generated by the oscillator 50. As shown in Fig. 3, this wave 53 consists of a series of pulses 53a which recur at intervals corresponding to a sub-multiple of the frequency of recurrence of the pulses 51a. These pulses will be synchronized rigidly with the pulses 51a from the master oscillator 50. In the particular illustration it will be observed that the pulses 53a recur at a frequency one half that of the recurrence of the pulses 51a. Also, for reasons that will shortly appear, the wave 53 has a fundamental frequency equal to the line scanning frequency.

The output of the multi-vibrator 52 is also impressed on a chain of multi-vibrators 54, 55 and 56 by means of which waves of successively decreasing fundamental frequency are produced. Each one of these waves has a fundamental frequency which is a submultiple of the fundamental frequency of the output wave of the preceding multi-vibrator. In this way all of the multi-vibrators are maintained in rigid synchronism, as is well understood in the art. The final wave 57 generated in the multi-vibrator 56 is of much lower fundamental frequency than the wave 51 and each pulse 57a lasts during the time interval T between the completion of one picture field and the start of a following field. The wave 57 has a fundamental frequency equal to the field frequency and is synchronized therewith.

The waves 51, 53 and 57 are the components of the composite synchronizing signal applied to the amplifier 43 in Fig. 1 over the conductor 45. The manner in which they are combined to form the desired composite synchronizing wave will now be outlined.

The outputs of the multi-vibrators 52 and 56 are both supplied to a mixer-clipper 58 in which the waves 53 and 57 are combined to form the wave 59. Various mixer-clipper circuits for accomplishing this result are known to those skilled in the art and the particular details are of no importance. Briefly, in one known form of circuit the wave 57 is added, in reversed polarity, to the wave 53. The resultant signal is applied to the grid of an amplifying device in which the grid voltage is adjusted in such a way that the device is driven beyond cutoff whenever this negative output wave 57 appears. The resultant is the wave 59 which corresponds to the wave 53 except that it is interrupted entirely during the time interval T in which a pulse 57a occurs.

The outputs of the multi-vibrators 56 and 50 are supplied to the mixer-clipper 60 in Fig. 2. In the mixer-clipper 60 the waves 51 and 57 are added in the same polarity and clipped to produce the resultant wave 61, which corresponds to the wave 51 except that it is switched on only during the time interval T in which a pulse 57a occurs.

The waves 59 and 61 are then combined to form the final composite synchronizing signal 62. The resultant wave 62 may optionally be clipped in the clipper 63 before it is applied to the conductor 45, to insure that all pulses are of equal height.

It will be observed from Fig. 3 that the composite synchronizing signal comprises a series of the pulses 53a which recur at line frequency. These pulses 53a are generated continuously except during each period of vertical synchronization between successive picture fields. During this time interval T the pulses 51a are transmitted. As previously mentioned, these pulses

51a recur at some frequency which is a multiple of the line frequency. In other words, the fundamental frequency of the synchronizing wave transmitted during the vertical synchronizing interval T is a multiple of the fundamental frequency of the wave transmitted during the remainder of the time. The manner in which this composite wave may be utilized in a television receiver, to effect horizontal and vertical synchronization of the cathode ray therein, will be reserved for discussion in connection with the description of the receiving system of Fig. 6.

As is indicated by the dashed lines in Fig. 2, the output of multi-vibrator 52, which comprises pulses recurring at the line frequency, may be supplied over the conductor 41 for synchronizing the horizontal deflection generator 35. Similarly the output of the multi-vibrator 56, which comprises pulses recurring at the field frequency, may be supplied over the conductor 42 to synchronize the vertical deflection generator 36. The outputs of these two multi-vibrators may further be combined to form the blanking pedestal which is applied to the conductor 44. This is schematically illustrated in Fig. 2 by the dashed rectangle which represents a pedestal mixer, and bears that legend, for carrying out this function. The details of these elements of the circuit of Fig. 2 are not material to my invention and are merely mentioned very briefly for the sake of completeness.

The circuit of Fig. 2, just described, is particularly adapted for use in a television system which does not employ interlaced scanning. It is readily adapted to interlaced scanning by making one slight modification, i. e., by synchronizing multi-vibrator 54 directly from the master oscillator 50. This alternative connection is indicated in Fig. 2 as being made by moving a switch 64 to the lower position. The frequency relationships between the various pulse generating elements will of course also be somewhat different for interlaced scanning, as will be apparent to those skilled in the art without further elaboration.

Fig. 4 illustrates diagrammatically an alternative form of the impulse generator 40 which is particularly suited for employment in the transmitting system of Fig. 1 when interlaced scanning is used. The curves of Fig. 5 will be considered in conjunction with Fig. 4 in outlining the operation of this form of the impulse generator. As in the case of the curves of Fig. 3, the curves of Fig. 5 are to be regarded as having a common horizontal time axis.

The master oscillator 70 in Fig. 4 generates a train of pulses which, for example, may be shaped into the general form illustrated by the wave 71 in Fig. 5. The output of the master oscillator 70 is utilized to synchronize the multi-vibrator 72. The fundamental frequency of the output wave 73 of this multi-vibrator is a sub-multiple of the fundamental frequency of the wave 71. As illustrated, the pulses 73a recur at a frequency one half that of the recurrence of the pulses 71a.

The output of the multi-vibrator 72 is impressed on the multi-vibrator 74, which generates the waves 75. The frequency with which the pulses 75a recur is a lower sub-multiple of the fundamental frequency of the wave 71 than in the case of the wave 73 and, for reasons which will shortly be apparent, the fundamental frequency of the wave 75 is made equal to the line scanning frequency. As illustrated, the pulses 75a recur at a frequency one fourth the frequency of recurrence of the pulses 71a.

The output of the multi-vibrator 72 is further impressed on a chain of multi-vibrators 76, 77, and 78 by means of which waves of successively decreasing fundamental frequency are produced. As in the case of the multi-vibrators 54, 55 and 56 of Fig. 2, each one of these waves has a fundamental frequency which is a sub-multiple of the preceding multi-vibrator, whereby all of the multi-vibrators are maintained in rigid synchronism with the master oscillator 70. The wave 79 generated in the multi-vibrator 78 comprises pulses 79a which recur at the field frequency and each of which lasts during the time interval T between the completion of one picture field and the start of a following field.

The output of the multi-vibrator 78 is supplied through a suitable delay circuit 80 to synchronize a multi-vibrator 81. The wave 82 generated by this multi-vibrator comprises pulses 82a which recur at the same fundamental frequency as the pulses 79a but which are delayed and narrowed with respect to the pulses 79a so that each pulse 82a is developed during the shorter time interval t . Apparatus by which this result may be accomplished is well known to the art and will not be discussed here. For example, one suitable circuit for carrying out this function is described in Patent No. 2,132,655, John P. Smith, issued October 11, 1938.

The waves 71, 73, 75, 79 and 82 are the components of the composite synchronizing signal impressed on the amplifier 43, in Fig. 1, over the conductor 45. The manner in which they are combined to form the desired signal is similar to that previously described in connection with Figs. 2 and 3, although somewhat more complicated.

The outputs of the multi-vibrators 78 and 74 are both supplied to the mixer-clipper 83 in which the wave 79, in reversed polarity, is added to the wave 75 and the resultant clipped to form the wave 84. This wave corresponds to the wave 75 except that it is interrupted during the time interval T in which a pulse 79a occurs.

The outputs of the multi-vibrators 72 and 73 are impressed on the mixer-clipper 85 in which the waves 73 and 79 are added together and clipped to form the wave 86. This wave corresponds to the wave 73 except that it is switched on only during the time interval T in which a pulse 79a occurs.

The output of the multi-vibrator 81 and the output of the mixer-clipper 85 are supplied to the mixer-clipper 87, in which the wave 82, in reversed polarity, is added to the wave 86 and the resultant clipped to form the wave 88. This wave also corresponds to the wave 73 except that it is, first, switched on only during the time interval T in which a pulse 79a occurs and, second, interrupted during the intervening time interval t in which a pulse 82a occurs.

The output of the master oscillator 70 and the output of the multi-vibrator 81 are impressed on the mixer clipper 89 in which the wave 82 is added to the wave 71 and the resultant clipped to form the wave 90. This wave corresponds to the wave 71 except that it is switched on only during the time interval t in which a pulse 82a occurs.

The outputs of the three mixer-clippers 83, 87 and 89 are combined to form the final composite synchronizing signal 91. The resultant wave 91 may optionally be clipped in the clipper 92 before it is supplied to the conductor 45 to insure that all pulses are of equal height.

In the composite wave 91 the pulses 75a, which

recur at line frequency, are those through which horizontal synchronization is accomplished. The pulses 73a constitute the so-called equalizing pulses which are commonly employed in interlaced scanning systems to improve the stability of interlace. The particular wave 91 illustrated is suitable for a system of double interlaced scanning, i. e., one in which two successive interlaced fields are required to produce a single complete picture image or frame. The composite synchronizing wave 91 is represented in the vicinity of the time interval including the end of one picture field and the start of the next field. In wave 92 the synchronizing wave is represented in the vicinity of the end of an alternate picture field. If we consider the beginning of pulse 79a as a reference point, it will be observed that the horizontal synchronizing pulses 75a in the respective portions of the waves 91 and 92 are displaced from each other in time by one-half the interval of recurrence. This is necessary in order to obtain proper interlace, as is well known to those skilled in the art. The function of the equalizing pulses 73 is to remove all influence of the unequal time intervals between the pulses 75a and 79a in alternate fields. This feature per se is well known in the art and forms no part of my invention. For a further understanding of the function of the equalizing pulses, reference may be had to Patent No. 2,192,121, Alda V. Bedford, issued February 27, 1940.

The time interval T, during which the pulses 73a and 71a occur in waves 91 and 92, is that of a vertical pedestal. The intervening interval t , during which the pulses 71a occur, is that of a vertical synchronizing signal. Thus, as is illustrated in waves 91 and 92, the pulses 71a which have a fundamental frequency which is four times the fundamental frequency of the pulses 75a, are transmitted during the vertical synchronizing period t . The equalizing pulses 73a, which have a fundamental frequency which is twice the fundamental frequency of the pulses 75a, are transmitted during that portion of the time period T of the vertical pedestal preceding and following the vertical synchronizing period t .

As is indicated by the dashed lines in Fig. 4, the output of the multi-vibrator 72 may be supplied to a multi-vibrator 93 which generates the horizontal synchronizing pulses recurring at the horizontal line frequency. The output of this multi-vibrator may be supplied over the conductor 41 for synchronizing the horizontal deflection generator 35 of Fig. 1. The output of the multi-vibrator 78, which comprises the broad pulses 79a recurring at field frequency during the time interval T between successive fields, may be employed to form the pedestal. The outputs of the multi-vibrators 78 and 93 may be combined in the pedestal mixer 94 and applied to the conductor 44 as illustrated. As in the case of the pulse generator of Fig. 2, the details of these elements of the pulse generator circuit are not material to an understanding of my invention and are mentioned only for the sake of completeness.

The synchronizing waves applied to the deflection generators 35 and 36 over the conductors 41 and 42, the blanking pedestal supplied over conductor 44, and the synchronizing signals supplied over conductor 45 are all synchronized with the master oscillator in the pulse generator 40. Therefore, as will be understood by those skilled in the art, all the components of the final wave

transmitted from the antenna 47 of Fig. 1 are maintained in their proper relationship.

The manner in which the transmitted synchronizing waves, as described above, are utilized at receiving apparatus will best be understood when considered in conjunction with the television receiving system illustrated in Figs. 6, 7, and 8.

Referring now to Fig. 6, the transmitted signal is received by the antenna 100. The initial stages of the television receiver apparatus are indicated collectively by the block 101. These may be conventional, comprising in the usual case the high frequency amplifier, oscillator, demodulator, and power amplifier circuits of the receiver. The demodulated television signal is supplied over the conductor 102 to the control element 103 of a cathode ray discharge device 104, by means of which an image corresponding to the received signal is reconstructed.

The cathode ray device 104 may be of any well known form and the details thereof form no part of my invention. Briefly, means are provided therein for developing and projecting an electron ray 105 against a fluorescent screen 106 on the end of the envelope. The intensity of the ray is varied in accordance with the signals applied to the control element 103. At the same time the ray is caused to scan the screen 106 in a pattern similar to that traced by the cathode ray 31 in the transmitter. This action is effected by deflecting the ray along coordinate axes by suitable means, illustrated as pairs of magnetic deflecting coils 107 and 108. Currents for energizing the deflecting coils 107 and 108 are supplied by the horizontal and vertical deflection generators 109 and 110, respectively.

The synchronizing signals, which also appear in the output of the television receiver 101, are clipped from the video signals in the synchronizing signal clipper 111 and supplied over the conductors 112 to the synchronizing signal separation circuit 113, to be described shortly in greater detail. In the separation circuit 113, horizontal and vertical synchronizing potentials are developed. These are indicated schematically as being supplied to the respective deflection generators 109 and 110 over the conductors 114 and 115. As is well known in the art, these potentials are utilized to trigger the deflection generators at the proper instants of time in order to effect synchronization of the scanning action.

The various elements of the receiving system of Fig. 6 are supplied with power from a suitable source, indicated schematically by the power supply source 99.

Fig. 7 represents one particular form of synchronizing signal separation circuit 113 which may be employed in the system of Fig. 6. This circuit discriminates between the horizontal and vertical synchronizing signals and separates them from each other. This separating action depends upon the frequency characteristics, i. e., the wave form, of the received composite synchronizing signal, and the function of the circuit will be better understood if the character of this signal is first considered.

Assume that the received composite synchronizing wave is of the wave form illustrated by the wave 62 of Fig. 3. The individual pulses contained in this wave are all substantially rectangular in shape. It is well known that any non-sinusoidal periodic wave may be resolved into a Fourier series of component waves, each of simple sinusoidal wave form. It is also a demon-

strable fact that a periodic wave composed of identical rectangular pulses recurring at regular intervals is analyzable into a fundamental sine wave, having a frequency equal to the rate at which the identical pulses recur, plus an almost infinite number of sine waves whose frequencies are different harmonics of the fundamental. Thus, the frequency of recurrence of the identical pulses determines the lowest frequency present in the sine waves of the series. The amplitude and duration of the individual pulses determine the magnitudes of the component waves and the particular harmonics present. Distortion of the rectangular wave form will not eliminate the fundamental though the magnitudes of the various component waves and the particular harmonics present will be altered. These sine waves of the Fourier series are not merely abstract mathematical quantities. They are physically realizable electrical waves which may easily be derived from the non-sinusoidal rectangular waves by suitable circuits.

Referring again to Fig. 7, assume that the composite synchronizing signal 62 of Fig. 3 is impressed on the conductors 112. This signal is applied through the conductor 114 to the horizontal deflection generator 109 in order to synchronize it at the fundamental frequency of the pulses 53a. It will be recalled that during the vertical synchronizing interval T the pulses 53a disappear, and the pulses 51a are substituted. These pulses have a higher fundamental frequency which is a harmonic of the pulses 53a, as previously explained. In the particular wave illustrated in Fig. 3 it is the second harmonic. It will be observed that the leading edges of alternate pulses 51a recur at precisely the same time intervals as the leading edges of the pulses 53a. As is well known to the art, it is a simple matter to keep the deflection generator 109 synchronized in accordance with alternate pulses 51a providing that these double frequency pulses have the correct leading edges and are present during the time interval T.

The signal received on conductors 112 is also impressed, through a series resistor 117, upon the tuned circuit 116 comprising an inductance and capacitor in parallel. This circuit is tuned to the fundamental frequency of the pulses 53a. Therefore, it has a high impedance to waves of that frequency and a very low impedance to waves of higher frequency, these latter being effectively grounded through the capacitor. Consequently, this tuned circuit is effective to separate the fundamental frequency component of the pulses 53a from the other harmonic components of the Fourier series composing the pulses 53a.

As long as the pulses 53a are received, oscillating potentials at their fundamental frequency appear across the tuned circuit 116. These potentials are applied, by means of a grid capacitor 118 and grid resistor 119 upon the control grid of a thermionic amplifier 120. The amplifier 120 is biased to operate as a grid detector and, in a manner well known to the art, the potentials impressed thereon from the tuned circuit 116 are rectified. The time constant of the capacitor 118 and resistor 119 is long compared to the period of recurrence of the pulses 53a, so that the rectified potentials maintain a substantially constant bias on the grid as long as the pulses 53a are impressed on the circuit. The anode potential of the amplifier 120 therefore remains substantially constant. Any ripple

at this frequency appearing in the anode circuit may further be filtered from conductor 115 by means of the resistor 121 and by-pass capacitor 122.

Now assume that a vertical synchronizing interval occurs, as is indicated by the time interval T in Fig. 3. The pulses 51a are now impressed upon the separation circuit of Fig. 7. The fundamental frequency of these pulses, as previously explained, is twice the frequency of pulses 53a and thus twice the resonant frequency of tuned circuit 116. Since the impedance of the tuned circuit is very low for any frequency higher than its resonant frequency, the potential impressed on the grid of amplifier 120 is suddenly decreased. The result is a transient variation in anode potential. This transient variation is transmitted as a pulse through the blocking capacitor 123 and resistor 121 to the conductor 115. Therefore, a pulse is impressed upon the vertical deflection generator 110 at every time interval T, in accordance with the transmitted signals.

When an interlaced picture is to be transmitted, the fact that there is a different time interval in alternate fields between the beginning of the vertical synchronizing interval T and the nearest horizontal synchronizing pulse may affect the quality of the interlace. One method of circumventing this trouble is to use the trailing edge of each vertical pulse for synchronization, rather than the leading edge.

Another method is to transmit the synchronizing signal 91, 92 of Fig. 5 and to tune the resonant circuit 116 of Fig. 7 to twice the fundamental frequency of the pulses 75a, i. e., to the fundamental frequency of the pulses 73a. Since this frequency is present in both waves, oscillating potentials will be developed across tuned circuit 116 when either pulses 75a or 73a are received. In the preferred forms of waves illustrated in Fig. 5, the widths of pulses 75a and 73a are made inversely proportional to their frequency of recurrence. It can easily be shown that, under these conditions, the amplitude of the oscillating potentials developed across tuned circuit 116 is constant irrespective of whether pulses 75a or 73a are received. Thus, no transient change in anode potential of device 120 occurs upon the transition from one group of pulses to the other. In some cases, it may be desired to make pulses 75a and 73a of equal widths. In this case the potential across tuned circuit 116 will increase at the beginning of time interval T and a transient pulse will be developed in the anode circuit of device 120. However, the resultant pulse transmitted to the vertical deflection generator 110 is of opposite polarity to the pulse developed at the beginning of the vertical synchronizing interval t and will not tend to cause false triggering of the generator 110.

A slightly different form of synchronizing pulse separation circuit 113 may be employed in the receiving system of Fig. 6 to provide additional protection against false vertical tripping. A circuit which will accomplish this is shown in Fig. 8.

In Fig. 8 the composite synchronizing signal 91, 92 of Fig. 5 is impressed upon two separate tuned circuits 130 and 131 through the series resistors 132 and 133 respectively. The circuit 130 is tuned to the fundamental frequency of the pulses 75a, whereas the circuit 131 is tuned to the fundamental frequency of the pulses 73a. The composite signal is also supplied over the conductor 114 in order to synchronize the horizontal deflection generator 109 in the same man-

ner as previously described in connection with the circuit of Fig. 7.

A portion of the potential appearing across the tuned circuit 130 is rectified by the diode detector circuit comprising the resistor 134, capacitor 135 and diode rectifier 136. A portion of the potential appearing across the tuned circuit 131 is also rectified by a similar diode detector circuit comprising the resistor 137, capacitor 138 and diode rectifier 139.

Potentials developed in the tuned circuits 130, 131 and rectified by the respective diodes 136 and 139 are impressed upon control elements of the thermionic amplifier 140, which is illustrated as of the pentode type. As shown, the anode of diode 136 is coupled to the screen grid 141 of the amplifier 140 through a coupling capacitor 142. A suitable positive potential is impressed on the screen grid 141 from a potential source, not shown, through a decoupling resistor 143.

The anode of diode 139 is coupled to the control grid 144 of the amplifier 140 by means of a grid capacitor 145 and grid resistor 146. The control grid 144 is also supplied with a suitable negative bias from a suitable potential source, not shown.

The operation of the separation circuit of Fig. 8 upon reception of the composite synchronizing wave 91, 92 is as follows: Assume first that pulses 75a are received. These cause oscillating potentials to be developed in the tuned circuit 130 which are rectified and applied through the capacitor 142 to the screen grid 141 in a negative sense. The time constant of the capacitor 142 and resistor 143 is sufficiently great so that this negative potential remains substantially constant over a vertical or framing interval and at a value sufficient to bias the amplifier 140 to an inoperative condition.

Assuming next that a group of equalizing pulses 73a are received, an oscillating potential is developed across the tuned circuit 131, rectified and applied through the capacitor 145 to the control grid 144 of the amplifier 140. This potential is applied to the grid 144 in a negative sense and is again of a value sufficient to maintain the amplifier 140 inoperative. Thus, when either the horizontal synchronizing pulses 75a or the equalizing pulses 73a are received, no current flows in the anode circuit of the amplifier 140.

Assume next that a group of vertical synchronizing pulses 71a is received. The potential applied to the grid 144 from the diode 139 disappears, since there is no component frequency present in the pulses 71a equal to the resonant frequency of the tuned circuit 131. Likewise, there is no component frequency present in these pulses equal to the resonant frequency of the tuned circuit 130, so no potential is applied to the screen grid 141 from the diode 136. The amplifier 140 is therefore unblocked and draws anode current. The result is a transient decrease in anode potential which is transmitted as a pulse through the blocking capacitor 147 and resistor 148 to the conductor 115. This pulse of voltage is effective to synchronize the vertical deflection generator 110, as previously described. Any ripple in this pulse due to frequencies present in the pulses 71a may be filtered from the conductor 115 by the resistor 148 and a by-pass capacitor 149.

It might also be noted at this point that the tuned circuit 130 and associated elements 132, 134, 135, 136, and 142 can be omitted entirely, if desired, to simplify the circuit. The operation

of the circuit is then essentially the same as previously described in connection with the modified form of the circuit of Fig. 7 wherein the circuit 116 is tuned to the fundamental frequency of the pulses 13a for operation with the synchronizing signal 91, 92 of Fig. 5. However, the circuit of Fig. 8 provides additional protection against false vertical tripping by reason of the fact that either one of the negative biasing potentials applied to the respective grids prevents change in anode potential of amplifier 140 until the vertical synchronizing pulses are received.

While the diodes 136 and 139 and the pentode 140 have been illustrated as separate devices, these elements may conveniently be combined in a single duplex-diode-pentode tube having a common cathode for the three groups of electrode elements.

In the specific form of synchronizing signal illustrated in Fig. 3 the vertical synchronizing pulses recur at twice the frequency of the horizontal synchronizing pulses. Similarly, in the specific form of synchronizing signal illustrated in Fig. 5 the vertical synchronizing pulses recur at four times the frequency of the horizontal synchronizing pulses and the equalizing pulses at twice this frequency. Of course these particular values are not limiting. The frequency relationships of the various pulses can be generalized as set forth below.

Consider first the general form of synchronizing signal, which may be utilized in a system operating either with or without interlaced scanning, but without equalizing pulses. If the fundamental frequency of the horizontal synchronizing pulses is f_h , it is necessary to make the fundamental frequency component of the vertical synchronizing pulses equal to $p f_h$ where p is any integer greater than unity. This insures that there will be no frequency component equal to f_h in the synchronizing signal during the vertical synchronizing period and enables the two signals to be separated in a simple frequency detecting circuit such as that of Fig. 7.

In the event that the synchronizing signal is utilized in an interlaced scanning system in which it is also desired to transmit equalizing pulses, the fundamental frequency of the vertical synchronizing pulses must be made equal to $pknf_h$, where p is any integer greater than unity, where k is any integer, where n is the number of interlaced picture fields in which one image is completely scanned and where f_h is the fundamental frequency of the horizontal synchronizing pulses. The fundamental frequency of the equalizing pulses will then be knf_h . The signals may be separated from each other by a circuit such as is shown in Figs. 7 and 8. If the circuit of Fig. 7 is used, then the circuit 116 should be tuned to knf_{hz} , since there is no frequency component present which is equal either to f_h or knf_h when the vertical synchronizing pulses, having a higher fundamental frequency $pknf_h$, are transmitted.

In the foregoing analysis the frequency f_h of the horizontal synchronizing pulses has been indicated as being the same as the line scanning frequency. While ordinarily it is preferable to have these two frequencies the same for practical reasons, there is no reason why f_h cannot be an integral multiple of the line scanning frequency. The above generalizations are then still valid, since potentials are continuously available for synchronizing the horizontal deflection generator by reason of the harmonic relationship be-

tween the line scanning frequency and all synchronizing signals.

In both the illustrated embodiments of the invention, the widths of the individual pulses in the synchronizing waves have been illustrated as being inversely proportional to their frequencies of recurrence. Thus, in Fig. 3, the pulses 51a are illustrated as being of half the width of the pulses 53a. Similarly, in Fig. 5, the pulses 11a and 13a are illustrated as being one-fourth and one-half the widths of the pulses 15a, respectively. Therefore, except for the slight dissimilarity between the synchronizing signals 91 and 92 of alternate frames in the vicinities of the initiation and termination of the time interval T , the average amplitude of the synchronizing signals remains substantially constant.

It has been pointed out previously that the illustrated relationship of pulse widths may be desirable when the synchronizing signal separation circuit of Fig. 7 is adapted to derive vertical synchronizing pulses from a signal containing equalizing pulses. This refinement also has the further advantage that the average amplitude of the composite synchronizing signal, as well as its maximum amplitude, is always substantially constant. Consequently, the apparatus for generating and transmitting the synchronizing signal may be designed for high efficiency operation on a substantially constant load.

Various well known forms of apparatus are available for generating pulses of any desired ratio of pulse width to frequency, and their design will be apparent to those skilled in the art without further elaboration.

While my invention has been described in its application to a television system, wherein it possesses particular utility, it will be apparent that it may also find utility in other forms of signalling systems. Broadly considered, my invention is applicable to electrical signalling systems in which a plurality of control signals are sequentially transmitted over a single channel, separated from each other at a receiving station and utilized to effect several individual and distinct indicating or controlling operations.

It will also be apparent from the foregoing description that the frequency band required to accommodate the synchronizing signals need not be unduly wide. Complete separation of the different signals is achieved even though their fundamental frequencies are separated from each other only in the ratios of small whole numbers. Thus, in the specific synchronizing signal illustrated in Fig. 3, the fundamental frequency of the wave 51 is only twice that of wave 53. Similarly, in Fig. 5 the fundamental frequency of wave 11 need only be four times that of wave 15 for a complete double interlaced scanning system utilizing equalizing pulses. The separation of the various signals may be secured without any possibility of interaction or false operation by virtue of the fact that each signal contains no fundamental frequency whatsoever lower than its fundamental frequency.

While I have shown particular embodiments of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. In the art of television, the method of pro-

viding a composite synchronizing signal for use in a system employing interlaced scanning comprising the steps of developing first synchronizing pulses recurring at a frequency f_h equal to the line scanning frequency or an integral multiple thereof and synchronized with successive scanning lines, interrupting said pulses during the time intervals between successive picture fields, developing equalizing pulses during said last mentioned intervals recurring at a frequency knf_h , where k is an integer and n is the number of interlaced picture fields in which the picture area is completely scanned once, interrupting said equalizing pulses during an intervening portion of each of said last mentioned intervals, developing second synchronizing pulses during said intervening portions recurring at a frequency $pknf_h$, where p is an integer greater than one, and combining said pulses to form a composite synchronizing signal.

2. In the art of television, the method of providing a composite synchronizing signal for use in a system employing interlaced scanning comprising the steps of developing substantially rectangular line synchronizing pulses which are synchronized with the intervals between successive trains of picture signals representative of lines of an image to be transmitted and which recur at a frequency f_h , interrupting said pulses during the time intervals between successive picture fields, developing substantially rectangular equalizing pulses during said last-mentioned intervals which recur at a fundamental frequency knf_h , where k is an integer and n is the number of interlaced picture fields in which said image is completely scanned, interrupting said equalizing pulses during an intervening portion of each of said last-mentioned intervals, developing substantially rectangular field synchronizing pulses during said intervening portions which recur at a fundamental frequency $pknf_h$, where p is an integer greater than one, and combining said pulses to form a composite synchronizing signal.

3. In the art of television, the method of providing a composite synchronizing signal comprising the steps of developing substantially rectangular line synchronizing pulses which are synchronized with the intervals between successive trains of picture signals representative of lines of an image to be transmitted and which recur at a frequency f_h , interrupting said pulses for a predetermined time during each of the time intervals between successive picture fields, developing substantially rectangular field synchronizing pulses in said last-mentioned intervals which recur at a fundamental frequency p_f_h , where p is an integer greater than one, and combining said synchronizing pulses to form a composite synchronizing signal, all said pulses being of substantially equal heights and of widths inversely proportional to their frequencies of recurrence, whereby the average amplitude of said signal is substantially constant.

4. In the art of television, the method of providing a composite synchronizing signal for use in a system employing interlaced scanning comprising the steps of developing substantially rectangular line synchronizing pulses which are synchronized with the intervals between successive trains of picture signals representative of lines of an image to be transmitted and which recur at a frequency f_h , interrupting said pulses during the time intervals between successive picture fields, developing substantially rectangular

equalizing pulses during said last-mentioned intervals which recur at a fundamental frequency knf_h , where k is an integer and n is the number of interlaced picture fields in which said image is completely scanned once, interrupting said equalizing pulses during an intervening portion of each of said last-mentioned intervals, developing substantially rectangular field synchronizing pulses during said intervening portions which recur at a fundamental frequency $pknf_h$, where p is an integer greater than one, and combining said pulses to form a composite synchronizing signal, all said pulses being of substantially equal heights and of widths inversely proportional to their frequencies of recurrence, whereby the average amplitude of said signal is substantially constant.

5. In a television system, a synchronizing pulse generator for synthesizing a composite synchronizing signal comprising, in combination, first means for generating a first series of substantially rectangular pulses recurring periodically at a frequency p_f_h , where p is an integer greater than one and f_h is the frequency of horizontal scanning or an integral multiple thereof, second means for generating a second series of substantially rectangular pulses recurring periodically at the frequency f_h , said pulses all being of substantially equal heights and of widths inversely proportional to their frequencies of recurrence, whereby the average amplitude of both said series is substantially the same, third means for generating a third series of substantially rectangular pulses recurring at the frequency of vertical scanning, means for transmitting said first series of pulses and for interrupting their transmission during the time intervals between the pulses of said third series, means for transmitting said second series of pulses and for interrupting their transmission during the time durations of the pulses in said third series, and means for combining said interrupted series of transmitted pulses to form a continuously transmitted composite synchronizing signal.

6. A television synchronizing system comprising, in combination, means for generating a first series of pulses synchronized with the intervals between successive scanning lines and recurring periodically at frequencies equal to the line scanning frequency or to an integral multiple thereof, means for generating a second series of pulses synchronized with said first series and recurring periodically at a frequency equal to a higher integral multiple of said line scanning frequency, means for transmitting said first series, means for interrupting the transmission of said first series for predetermined time intervals occurring between successive picture fields and for transmitting said second series during each of said intervals, means for receiving said transmitted pulses, a line deflection generator adapted to be synchronized at any of said frequencies, means supplying all said received pulses to said generator for continuously synchronizing its operation, means for deriving a field synchronizing pulse from said received pulses in response to the disappearance of a component frequency of said first pulses during said intervals, said component frequency being lower than the frequency of recurrence of the pulses in said second series, a field deflection generator adapted to be synchronized at the frequency of recurrence of said field synchronizing pulses, and means supplying said field synchronizing pulses to said field de-

fection generator for synchronizing its operation.

7. In a television system having means for receiving a continuous composite synchronizing signal, said signal being composed of a plurality of electrical waves consecutively arranged in a predetermined time sequence, certain of said waves containing components of a particular frequency and higher frequency harmonics thereof, at least one other of said waves being composed only of higher frequency harmonics of said frequency, means for impressing said signal upon a frequency responsive device, said device being adapted to develop substantial voltages during intervals when said frequency is present in said signal and relatively low voltages during intervals when said frequency is absent, and means responsive to the transient decrease in said voltages at the beginning of each of said last mentioned intervals for developing a synchronizing pulse.

8. In a television system having means for receiving a continuous composite synchronizing signal composed of sequentially recurring groups of pulses, one or more of said groups comprising pulses recurring at the line scanning frequency or an integral multiple thereof, another of said groups comprising pulses recurring at a higher integral multiple of said frequency, means for impressing said signal on a frequency responsive device adapted to develop substantial voltages during receipt of said first mentioned groups and relatively low voltages during receipt of said last mentioned group, a thermionic amplifier having input and output circuits, means for biasing said input circuit in response to said voltages, and means responsive to current variations in said output circuit for developing field synchronizing pulses.

9. In a television system having means for receiving a continuous composite synchronizing signal composed of sequentially recurring pulse groups, certain of said groups being composed of pulses recurring at the line scanning frequency or an integral multiple thereof and synchronizing with successive scanning lines, said pulses containing a particular frequency component and harmonics thereof, another of said groups being composed of pulses recurring at a harmonic of said particular frequency and occurring within intervals between successive picture fields, means for impressing said signal upon a tuned circuit resonant at said particular frequency, said circuit having substantial voltages developed thereon only when said particular frequency is present in said signal, a thermionic device having a control grid and anode, means for detecting said voltages and biasing said grid in accordance therewith, an output impedance coupled to said anode, and means responsive to change in anode current through said impedance for developing field synchronizing pulses.

10. In a television system having means for receiving a continuous composite synchronizing signal composed of sequentially recurring groups of pulses, one of said groups comprising line synchronizing pulses having a fundamental frequency f_h , another of said groups comprising equalizing pulses having a fundamental frequency knf_h , where k is an integer and n is the degree of interlace, and still another of said groups comprising vertical synchronizing pulses having a fundamental frequency $pknf_h$, where p is an integer greater than one, means for impressing said signal upon two frequency respon-

sive elements tuned respectively to the frequencies knf_h and $pknf_h$, each of said elements being adapted to develop a substantial voltage thereon only at its resonant frequency, a thermionic device having at least two grids and an anode, means for biasing each of said grids in response to one of said voltages and in a sense to render said device inoperative, said last means comprising a rectifier circuit energized from each element and coupled to one of said grids, whereby said device becomes operative and draws substantial anode current only when said groups of vertical synchronizing pulses are received, a vertical deflection generator, and means responsive to said anode current for synchronizing said generator.

11. The method of synchronizing a plurality of different electrical effects at a receiving point with corresponding electrical effects at a transmitting point which comprises transmitting between said points a first wave containing a particular frequency component, interrupting the transmission of said wave at intervals, transmitting during said intervals a second wave having a fundamental frequency which is a higher frequency harmonic of said particular frequency, whereby said particular frequency is absent during said interruptions, synchronizing one of said effects with either of said frequencies, whereby said effect is synchronized continuously by one or another of said waves, and synchronizing another of said effects with the occurrence of the interruptions in said first wave.

12. The method of controlling a plurality of electrical operations at a receiving point with waves transmitted over a single channel which comprises generating a plurality of periodic electrical waves at a transmitting point, all but one of said waves containing a particular frequency, said one wave having its lowest frequency higher than said particular frequency and harmonically related thereto, consecutively transmitting said waves over said channel in a predetermined sequence, effecting a first control operation continuously in response to receipt of any of said frequencies, and effecting a second, independent control operation in response to the disappearance of said particular frequency when said one wave is transmitted.

13. The method of controlling a plurality of electrical operations at a receiving point with waves transmitted over a single channel which comprises generating a plurality of periodic electrical waves at a transmitting point, all but one of said waves containing a particular frequency, said one wave having a fundamental frequency higher than said particular frequency and harmonically related thereto, consecutively transmitting said waves over said channel in a predetermined sequence, effecting a first control operation continuously in response to receipt of any of said frequencies, developing an electrical effect in response to receipt of said particular frequency, developing a control signal in response to transient changes in said effect upon disappearance of said particular frequency, and effecting a second, independent control operation in response to said control signal.

14. In the art of television, the method of synchronizing two different scanning operations at a receiving point with waves transmitted over a single channel which comprises generating a plurality of periodic electrical waves at a transmitting point, all but one of said waves containing a particular frequency, said one wave hav-

ing a fundamental frequency higher than said particular frequency and harmonically related thereto, consecutively transmitting said waves over said channel in a predetermined regular sequence, each wave being interrupted when any other of said waves is transmitted, synchronizing one of said scanning operations continuously first by one and then another of said frequencies, and synchronizing the other of said scanning operations in response to the disappearance of said particular frequency when said one wave is transmitted.

15. In the art of television, the method of synchronizing the scanning actions of a television transmitter and receiver which comprises transmitting a wave containing a particular frequency component, interrupting the transmission of said wave at periodically recurring intervals, transmitting during said intervals a wave having a fundamental frequency higher than said particular frequency and harmonically related thereto, whereby said particular frequency is absent during said intervals, receiving said waves, effecting line synchronization continuously first by one and then the other of said frequencies, and effecting field synchronization with the interruptions in said first wave in response to the disappearance of said particular frequency component.

16. The method of synchronizing a television transmitter and receiver which comprises generating first synchronizing pulses recurring at the line scanning frequency or an integral multiple thereof, generating second synchronizing pulses recurring at a higher integral multiple of said line scanning frequency, transmitting said first pulses, interrupting the transmission of said first pulses for predetermined time intervals occurring between successive traversals of the picture field, transmitting said second pulses during said intervals, effecting line synchronization from any of said pulses, developing a control potential in response to receipt of a frequency component of said first pulses lower than the frequency of recurrence of said second pulses, deriving an individual and distinct synchronizing signal in response to transient changes in said control potential caused by the disappearance of said frequency component during said time intervals, and effecting field synchronization from said signal.

17. The method of synchronizing the scanning actions of a television transmitter and receiver which comprises transmitting first substantially rectangular synchronizing pulses recurring at the line scanning frequency or an integral multiple thereof, interrupting the transmission of said pulses at regular intervals, transmitting during said intervals second substantially rectangular synchronizing pulses recurring at a higher integral multiple of said line scanning frequency, effecting line synchronization in response to receipt of either of said pulses and effecting field synchronization in response to the occurrence of the interruptions in said first pulses.

18. A system for synchronizing the scanning actions of television transmitting and receiving apparatus comprising means for transmitting between said apparatus a first wave containing a particular frequency component, means for periodically interrupting the transmission of said wave at intervals, means for transmitting during said intervals a second wave having a fundamental frequency higher than said particular

frequency and harmonically related thereto, a line deflection generator adapted to be synchronized at either of said frequencies, means for impressing said waves on said generator to synchronize its operation, a field deflection generator adapted to be synchronized at the frequency of the interruptions in said first wave, and means responsive to the occurrence of said interruptions for synchronizing the operation of said field deflection generator.

19. A system for synchronizing the scanning actions of a television transmitter and receiver comprising means for transmitting first substantially rectangular synchronizing pulses recurring at the line scanning frequency or an integral multiple thereof, means for interrupting the transmission of said pulses at regular intervals, means for transmitting during said intervals second substantially rectangular synchronizing pulses recurring at a higher integral multiple of said line scanning frequency, a first deflection generator adapted to be synchronized at any of said frequencies, means for impressing said pulses on said generator to synchronize its operation, a second deflection generator adapted to be synchronized at the frequency of interruption of said first pulses, and means responsive to the occurrence of said interruptions for synchronizing the operation of said second generator.

20. In a system for synchronizing a television transmitter and receiver, means for generating first synchronizing pulses recurring at the line scanning frequency or an integral multiple thereof, means for generating second synchronizing pulses recurring at a higher integral multiple of said line scanning frequency, means for transmitting said first pulses, means for interrupting the transmission of said first pulses for predetermined time intervals occurring between successive traversals of the picture field and for transmitting said second pulses during said intervals, means for effecting line synchronization in response to receipt of any of said pulses, and means for effecting field synchronization in response to the disappearance of a component frequency of said first pulses during said intervals, said component frequency being lower than the frequency of recurrence of said second pulses.

21. In a system for synchronizing a television transmitter and receiver, means for generating first synchronizing pulses recurring at the line scanning frequency or an integral multiple thereof, means for generating second synchronizing pulses recurring at a higher integral multiple of said line scanning frequency, means for transmitting said first pulses, means for interrupting the transmission of said first pulses for predetermined time intervals occurring between successive traversals of the picture field and for transmitting said second pulses during said intervals, means for effecting line synchronization in response to receipt of any of said pulses, means for developing a control potential in response to receipt of a component frequency of said first pulses lower than the frequency of recurrence of said second pulses, means for developing a synchronizing signal in response to transient changes in said control potential caused by the disappearance of said component frequency during said time intervals, and means for effecting field synchronization in response to said control signal.

22. In a television system, a synchronizing pulse generator for synthesizing a composite synchronizing signal comprising, in combination, means for generating first substantially rec-

tangular synchronizing pulses recurring at the line scanning frequency or an integral multiple thereof and synchronized with successive scanning lines, means for transmitting said pulses to a signal channel, means for interrupting their transmission during predetermined time intervals occurring between successive picture fields, means for generating second substantially rectangular synchronizing pulses recurring at a

higher integral multiple of said line scanning frequency, means for transmitting said second pulses to said channel only during said intervals, all said pulses being of substantially equal heights and of widths inversely proportional to their frequencies of recurrence, whereby the average amplitude of said composite signal transmitted to said channel is substantially constant.

EVERHARD H. B. BARTELINK.
